(57) **CLAIM**

(**) Term: **14 Years**

We claim the ornamental design for an adjustable semi-con shield shaving tool, as shown and described herein.

(21) Appl. No.: **29/170,094**

DESCRIPTION

(22) Filed: **Oct. 30, 2002**

FIG. 1 is a perspective view of an adjustable semi-con shield shaving tool in accordance with the present invention.

(51) LOC (7) Cl. **08-03**

FIG. 2 is a right side elevational view of an adjustable semi-con shield shaving tool as seen in FIG. 1.

(52) U.S. Cl. **D8/98; D8/51**

FIG. 3 is a left side elevational view of an adjustable semi-con shield shaving tool as seen in FIG. 1.

(58) Field of Search D8/98, 51, 52;

FIG. 4 is a front side elevational view of an adjustable semi-con shield shaving tool as seen in FIG. 1.

30/90.1, 90.2, 90.3, 90.4, 90.5, 90.6, 90.7,
90.8, 90.9, 91.1, 91.2; 81/9.4, 9.42, 9.43

FIG. 5 is a back side elevational view of an adjustable semi-con shield shaving tool as seen in FIG. 1.

(56) **References Cited**

FIG. 6 is a top plan view of an adjustable semi-con shield shaving tool as seen in FIG. 1; and,
